BURR-REMOVING ATTACHMENTS FOR SCREW-SLOTTING MACHINES

Joseph M. Schaeffer, Waterbury, Conn., assignor to The Waterbury Farrel Foundry and Machine Company, Waterbury, Conn., a corporation of Connecticut

Application April 5, 1952, Serial No. 280,767

13 Claims. (Cl. 10—6)

This invention relates to screw-slitting machines and more particularly to devices of this character known as high speed screw-slitting machines in that the screws are fed continuously to the machine and are slotted during their travel therethrough. This enables the work to be carried on at a very rapid rate as contrasted with another common type of slitting machines wherein the blanks remain stationary in the machine during the slitting operation.

In the type of machine with which the present application is concerned, the screws are fed to a rotary dial and are carried through the machine by this dial. The dial is hollow, and mounted eccentrically within the dial is a central screw-slitting saw. The saw rotates in a direction opposite that of the dial and due to the eccentricity of the two rotating members the space between the cutting edge of the saw and the inner periphery of the dial is such that the saw would not come in contact with the head of a blank carried by the dial during a large part of its movement. However, the saw will contact the head of the blank during approximately 90 degrees of its travel. It thus effectively slots each screw and moreover is in engagement with a number of blanks or screw heads at one time so that there is no abrupt shift or change over from one blank to another.

The carrying dial is in the form of a ring member provided with a plurality of radial grooves upon one face to hold the shanks or bodies of the blanks. It is necessary that the blanks be held against rotation while they are in contact with the saw and also that they be prevented from dropping out of the carrying dial once they have been entrained therein. Means are provided for this purpose in the form of a pressure pad, adjustably mounted in front of the carrying dial so that this pressure pad will bear against the shanks or bodies of the blanks and hold them in place in the dial. Also a retaining ring is secured to this pressure pad to lie radially inwardly of the carrier dial and engage the heads of the blanks to prevent them from dropping out of the dial.

In connection with the slitting of some types of screws, a burr is left at the edge of the slot formed in the head of the screw, and it is desirable to provide the slitting machine with a trimming or deburring cutter to remove these burrs. The present application deals particularly with the provision of means for this function.

For this purpose an insert is set into the rear face of the pressure pad at a point in the latter following that portion thereof wherein the saw engages the blanks. This insert is roughened or knurled upon its outer face so that when the blanks in their travel about the axis of the carrier are engaged by the knurled surface of the insert, they are caused to rotate upon their axes. Also secured to the pressure pad at approximately the same circumferential position as the insert just described is a cutter so arranged that it engages the heads of the screws during their rotation to trim or cut the burrs therefrom.

One object of the present invention is to provide a

2

new and improved high speed slitting machine for the slotting of screw or bolt blanks or the like.

Another object of the invention is to provide a high speed screw-slitting machine having a continuously rotating carrying dial with improved means for removing the burrs from the slotted screw heads during their movement through the machine by the carrier.

A still further object of the invention is to provide a high speed screw-slitting machine having a continuously rotating carrying dial for the blanks with a member mounted upon a fixed point of the machine with which the blanks are caused to engage during the rotation of the carrier, this member having a knurled surface to rotate the blanks when in engagement therewith and to provide a cutter upon a fixed part of the machine at the proper position such that the heads of the blanks will be rotated in engagement with the cutting means to remove the burrs therefrom.

A still further object of the invention is the provision in a machine of the character described above of a single cutter occupying a given station in the travel of the blanks and means for rotating the blanks when opposite this station so that the cutter will trim the burrs from the heads of the blanks.

To these and other ends the invention consists in the novel features and combinations of parts to be herein-after described, and claimed.

In the accompanying drawings:

Fig. 1 is a front elevational view of a portion of a screw-slitting machine embodying my invention;

Fig. 2 is a sectional view on line 2—2 of Fig. 1;

Fig. 3 is a detail sectional view on line 3—3 of Fig. 1;

Fig. 4 is a sectional view on line 4—4 of Fig. 3;

Fig. 5 is an elevational view of a portion of the rear face of the pressure pad on line 5—5 of Fig. 3;

Fig. 6 is a top view of a trimming or burr-removing cutter;

Fig. 7 is a front view of a screw-slitting machine embodying a modified form of my invention;

Fig. 8 is a perspective view of the insert or block having serrations thereon to engage and turn the blank during the burr-removing operation;

Fig. 9 is an enlarged top plan view of a portion of the block shown in Fig. 8;

Fig. 10 is an enlarged sectional view on line 10—10 of Fig. 7;

Fig. 11 is a view of the pressure pad used in the form of my invention shown in Fig. 7;

Fig. 12 is a sectional view on line 12—12 of Fig. 10 showing the burr-removing cutter in engagement with the work;

Fig. 13 is a view similar to Fig. 11 showing a pressure pad of modified form; and

Fig. 14 is a top view of the retaining ring adjacent the cutter.

To illustrate a preferred embodiment of my invention, I have shown in the drawings a screw-slitting machine having a stationary head 10 (Fig. 2) to which is secured a bearing sleeve 11 by bolts 12. Within the bearing sleeve is rotatably mounted the shaft 13 upon the forward end of which is secured the saw or cutter 14 by the clamping members 15 and 16 and nut 17.

The head 10 is a ring-like member and rotatably mounted within the head is the hub 18 of a gear 19, the hub being carried upon anti-friction bearings 20 and 21 so that the gear will be freely rotatable independently of the shaft 13.

The carrier dial 23 is secured to the forward face of the gear 19 by pins 24 and screws 24a. This carrier dial comprises an annular member having a plurality of radial grooves 25 (Fig. 1) cut into its forward face, which grooves are adapted, as shown in this figure and

3

also in Fig. 2, to receive the bodies of the blanks 26 with the heads of the blanks directed inwardly or toward the radius of the carrier dial.

From Fig. 2 of the drawings it will be apparent that while the shaft 13 is mounted in the bearing sleeve 11, the carrier dial which is secured to the gear 19 is mounted in an opening in the stationary head 10 by the ball bearings 20 and 21. The opening in the head which receives the bearings is slightly eccentric to the axis of the shaft 13 so that, as shown in Fig. 1, the saw 14 will be eccentrically mounted with respect to the inner periphery of the carrier dial 23. From inspection of this figure, it will be seen that at the righthand side of the figure the teeth of the cutter approach the inner periphery of the carrier ring more closely than at the lefthand side of the figure and, as shown in dotted lines at the right, the teeth of the cutter will engage the heads of blanks 26 for approximately 90 degrees of their travel about the axis of the cutter. It is also preferable to rotate the cutter in a direction opposite to the direction of rotation of the carrier dial, and means, not shown, are provided to effect rotation of these parts in opposite directions.

Blanks may be delivered to the machine by a chute between spaced members 27 and 28 (Fig. 2) and, as also shown in Fig. 1, this chute may be provided with a cover plate 29 to prevent the blanks being dislodged from the chute, the blanks traveling along the chute with their heads upwardly between the cover plate and the members 27 and 28. When the blanks reach the end of this chute they are picked up by an indexing wheel 31 mounted on a vertical shaft 32 and rotated by any suitable means, not shown. This wheel carries the blanks through an arc of approximately 180 degrees from the chute to the carrier wheel 23 (Fig. 2) where they are picked up by the latter and carried about the periphery of the saw.

It is, of course, necessary to provide some means to prevent blanks from becoming dislodged from the grooves 25 of the carrier wheel 23, and also to hold them in place with sufficient pressure so that they will be properly operated upon by the cutter 14, and the means for effecting this result will now be described.

As shown in Fig. 2, a cover plate 35 is secured to the face of the stationary head 10 by screws 36, this cover plate being a ring-like member extending through an angle of substantially 270 degrees, one edge of it being shown at 37 and the opposite edge being shown at 38. As shown in Fig. 2, the opening in this member is of greater diameter than the carrier dial 23.

Mounted within this opening in the cover plate 35 is a pressure pad 40 of arcuate shape and of substantially three quarters of a circle in extent, this pad being held in place by its engagement with the inner circumference of the cover plate and being held against rotation by a key 41 (Fig. 2) secured by a screw 42 to the cover plate. The lower edge of this key enters a recess 43 in the pressure pad so as to permit the latter to move toward and from the carrier dial 23 or axially of the shaft 13 while preventing it from rotating.

Secured to the inner periphery of the pressure pad by screws 45 is a retainer ring 46 having at its inner edge a flange 47 which lies against the head of the blank and holds it in one of the grooves in the carrier dial. The grooves in the carrier dial are preferably somewhat shallower than the diameters of the bodies of the blanks so that the latter project slightly from the surface of the dial, and it will be seen from Fig. 2 that the inner edge of the pressure pad 40 bears against the bodies of the blanks and holds them against rotation while the retainer ring 46 holds them against movement in a direction radially of the carrier.

It is necessary to apply pressure to the pressure pad in order to cause the inner surface thereof to bear against

the blanks, and this is effected by means of a spring plate 50 shown in Fig. 1. This plate is secured to the cover plate 35 by screws 51 and is slotted, as shown at 52 and 53, to provide resilient fingers 54, the inner ends of which extend radially to a position opposite the pressure pad 40. It will be seen from Fig. 1 of the drawings that this spring plate is of slightly less extent circumferentially than either the pressure pad 40 or the cover plate 35.

Adjusting screws 55 are threaded in the spring fingers 54 adjacent the inner ends thereof, which screws bear against the pressure pad 40 to urge the latter inwardly against the blanks. It will be understood that as the fingers 54 are resilient, the pressure upon the pad may be varied by the threaded adjustment of the screws 55, and as there are a number of these fingers, the pressure at one point may be varied with respect to that at another point. For example, the large opening 53 in the spring plate 50 is provided to permit the mounting of a bracket 56 (Fig. 1) to support a cutter for trimming the burrs from the blanks. At this point it is desirable to decrease the pressure so that the blanks may rotate and, with the independent spring fingers 54, each having an adjusting screw at its inner end bearing against the pressure pad, this adjustment may be readily effected.

The bracket 56, shown more particularly in Fig. 3, is secured by screws 57 to the face of the pressure pad 40 at the zone of the latter where the heads of the blanks are no longer engaged by the slotting saw. To the lower surface of the bracket is secured a cutter blade 58 having a cutting edge 59 thereon. The edge 59 may be of any desired form depending upon the shape of the head of the screw so that it will properly engage this head and remove the burr therefrom.

As shown in Fig. 3, the cutter is secured to the bracket 56 by the screw 60 which is received in an elongated or enlarged slot 61 so that the cutter blade may be adjusted toward and from the carrier dial 23 in order that the cutting edge will have proper engagement with the head of the blank. It will, of course, be understood that as the cutter is mounted upon the pressure pad, it will be resiliently urged toward the carrier dial by the spring fingers 54 which urge the pressure pad inwardly.

Upon the rear face of the pressure pad at a position substantially opposite the bracket 56 and cutter 58, a recess 62 is provided, and in this recess is seated an insert 63, the outer face of which is knurled or roughened, as shown in Fig. 5, the insert being secured in place by the screws 64. This insert is of arcuate shape and the roughened surface thereof will engage the shanks of the blanks, and the latter are carried past the insert by the carrier dial, thus effecting rotation of the blanks with the heads thereof in engagement with the edge 59. It will also be understood that the cutter blade 58 is of arcuate shape in cross section so that it will fit closely against the inner periphery of the pressure pad 40, the body of the blade lying in a recess in the outer surface of the retaining ring 46.

In the form of my invention previously described the knurled insert 63 (Fig. 5) which engages and rotates the blanks during the deburring operation is secured fixedly to the pressure pad 40, and, therefore, moves in and out with this pressure pad toward and from the carrier dial as adjusted by the screws 55. In some cases where there is a variation in the diameters of the blanks, it may be desirable to provide a separate block or insert, the position of which may be varied relatively to the pressure pad 40, this block being serrated to rotate the blanks and engaging them adjacent the burr-removing cutter. Also in this event it may be desirable to form the spring plate (the plate 50 of Fig. 1) in two or more sections so as to provide a separate section of the spring plate to bear against the insert or block which is slidably mounted in the pressure pad so that the spring pressure upon this block or insert can be adjusted entirely independently of

the spring pressure applied to the remainder of the pressure pad.

Such a construction is shown in Figs. 7 to 13 of the drawings, and the burr-removing cutter shown in these figures is also of a form somewhat different than that described above. As illustrated in Fig. 10 the head of the slotting device is shown at 10 to which is secured a cover plate 35 similar to that previously described. Also mounted within the opening of this cover plate is a pressure pad 64^b of the form shown in Fig. 11, the pad being of arcuate form and comprising an arc of substantially 270 degrees.

Secured to the cover plate 35, as shown more especially in Fig. 7, is the spring plate 65 which, as will be noted, is of less extent than the plate 50 shown in Fig. 1. This plate is slotted, as shown at 66, so as to provide resilient fingers 67, and adjusting screws 68 are threaded into these fingers and bear against the pressure pad to urge the latter toward the carrier dial 23. Adjustment of the screws will, of course, vary the pressure exerted by the pressure pad upon the blanks.

A spring plate section 69 of the same form as the plate 65 but formed separately therefrom is also secured to the cover plate 35 by the screws 70 (Fig. 10), and this plate is of smaller area than the plate 65 as it only operates during that portion of the travel of the blank during which the burr is removed. An adjusting screw 71 is mounted in the inner end of the plate section 69.

It will be noted from Fig. 11 that the pressure pad 64^b is provided with a cut-out portion or recess 72 and in this recess is slidably mounted an insert or block 73 which may move toward and from the carrier dial independently of the pressure pad. A block 74 on the rear of the member 73 is adapted to be contacted by the inner end of the adjusting screw 71 so as to adjust the pressure of the insert on the blank. On the inner face of the insert 73 is a face plate member 75 carrying serrations 76 upon its inner face so that, as shown in Fig. 10, the blank 26 will be engaged by these serrations and caused to rotate within the recesses or grooves of the carrier dial 23. The length or the extent of the serrated portion 76 which engages the blank is sufficient only to engage one blank at a time so that the blanks will always be positively rotated. Otherwise, if two blanks were engaged by the member 75 at the same time and one was slightly larger in diameter than the other, the larger one would control and the smaller one would not be rotated and, therefore, would not have the burr removed. It may be found convenient to have the face of the member 75 somewhat longer than necessary and if the entire length is serrated the serrations may be cut back, as shown at 77, or the portion of the block left smooth at this point so that the blank would only be engaged by the serrations 76 and there being only a sufficient movement of these serrations to engage one blank at a time in the rotation of the carrier dial.

In this form of my invention I also employ a retainer ring 46 similar to that shown in Fig. 2. A burr-removing cutter 80 is secured to this retainer ring by the screw 81, and it will be noted that the opening 82 in the retainer ring through which the screw passes is slightly larger than the body of the screw so that the cutter 80 may be adjusted toward and from the carrier dial and the blanks therein.

The form of cutter is shown in Figs. 10 and 12, and it will be seen that it is a double ended cutter having cutting edges 83 and 84 and it is also provided with two openings 85 for the screw 81 so that the cutter may be reversed in position and either edge employed as the cutting edge. As shown in Fig. 7, the cutter is of arcuate shape in cross section so as to fit snugly within the retainer ring 46 which is of arcuate form and against the insert 73, the lower surface of which is also of arcuate form. The cutter may be provided with a plane edge, as shown, the edge being of arcuate form so as to engage

the proper point on the blank as the latter is carried over its arcuate path. The form of the blade may, of course, vary depending upon the shape of the head of the screw which is being slotted. As shown, the cutter is beveled at 86 to match the bevel of the head of a flat-head screw. Upon the upper side of the cutter is provided a clearance angle 87 leaving an arcuate cutting edge which will engage the blank at the proper point during its revolution to remove the burr at the end of the slot. As shown in Fig. 12, the edge of the cutter is substantially parallel with the face of this dial. The contour of the edge of the cutter will, of course, be suited to the shape of the head of the screw being operated upon.

In the event that the edge of the cutter does not line up with the burr to be removed from the screw head, the cutter 14 may be adjusted so as to cut a deeper or shallower groove in the head of the screw which will, of course, make a corresponding difference in the position of the burr. Considerable tolerance is permitted in the depth of the screw slot so that when a cutter is employed having the contour required by the shape of the head, the edge of the cutter will be at the proper point to remove the burr from the head of the screw.

In some instances where long screws are being treated, the threads will not extend all the way to the head of the screw. In this event, it is undesirable to have the serrations 76 engage the blank adjacent the head as any marks left by these knurlings or serrations would not be removed during the threading operation. When such screws are to be slotted, I employ the pressure pad 64^a shown in Fig. 13 wherein the recess or cut-out portion 72^a is provided upon the outer circumference of this pad instead of upon its inner circumference. The insert or block 73 is slidably mounted in the recess 72^a as described in connection with the pressure pad 64^b shown in Fig. 11, and the backing member 74 upon the insert 73 will be engaged by the screw 71 as before. However, when long blanks are being slotted and the insert is placed at 72^a in the pressure pad 64^a, it is necessary to move the spring plate 69 radially outwardly. It will be noted from Fig. 7 that the cover plate 35 is provided with openings 90 disposed outwardly from the position of the screws 70. The plate 69 may be moved outwardly so that the screws 70 will enter the openings 90, and this will result in the screw 71 being disposed at the proper radial distance from the center of the pressure pad to engage the block 74 when the latter is in the recess 72^a.

While I have shown and described some preferred embodiments of my invention, it will be understood that it is not to be limited to all of the details shown, but is capable of modification and variation within the spirit of the invention and within the scope of the claims.

What I claim is:

1. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, means for retaining the blanks in said grooves during rotation of the carrier, a trimming cutter non-rotatably mounted on the machine in spaced relation to the face of the carrier past which cutter the blanks are carried by the carrier after engagement with the slotting cutter, and relatively stationary means for rotating said blanks on their axes as they are carried past said trimming cutter to trim the burrs therefrom, said trimming cutting being disposed on the side of the blanks opposite the carrier.

2. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, means for retaining the blanks in said grooves during rotation of the carrier, a trimming cutter

non-rotatably mounted on the machine in spaced relation to the face of the carrier past which cutter the blanks are carried by the carrier after engagement with the slotting cutter, and relatively stationary means for rotating said blanks on their axes as they are carried past said trimming cutter to trim the burrs therefrom, said trimming cutter being disposed on the side of the blanks opposite the carrier and being adjustable toward and from the carrier dial.

3. In a screw-slotting machine, a rotatably mounted carrier comprising a ring-like member having radial grooves in its face to receive the blanks, retaining means for retaining the blanks in said grooves, a slotting cutter rotatably mounted within the carrier, the axis of the cutter being eccentric to that of the carrier, means for rotating the cutter and carrier, a trimming cutter non-rotatably mounted on the machine past which the blanks are carried by the carrier after engagement with the slotting cutter, means for rotating said blanks on their axes as they are carried past said trimming cutter by the carrier to trim the burrs therefrom, said rotating means comprising a knurled member non-rotatably mounted on the machine in position to engage a part of the blanks as they are carried past said member by the carrier dial, and spring means for urging said rotating means toward the blanks.

4. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, a pressure member non-rotatably mounted opposite the face of the carrier to engage the bodies of the blanks and hold them in place, a trimming cutter mounted on said pressure member in position to engage the heads of the blanks as they are carried around by the carrier after being slotted by the slotting cutter, and means to rotate the blanks as they are carried past the trimming cutter.

5. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, a pressure member non-rotatably mounted opposite the face of the carrier to engage the bodies of the blanks and hold them in place, a trimming cutter mounted on said pressure member to engage the heads of the blanks as they are carried around by the carrier after being slotted by the slotting cutter, and means to rotate the blanks as they are carried past the trimming cutter, said rotating means being mounted on the pressure member.

6. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, a pressure member non-rotatably mounted opposite the face of the carrier to engage the bodies of the blanks and hold them in place, a trimming cutter mounted on said pressure member to engage the heads of the blanks as they are carried around by the carrier after being slotted by the slotting cutter, means to rotate the blanks as they are carried past the trimming cutter, and said trimming cutter being adjustable toward and from the carrier relatively to the pressure member.

7. In a screw-slotting machine, a rotatably mounted carrier comprising a ring-like member having radial grooves in its face to receive the blanks, a slotting cutter rotatably mounted within the carrier, the axis of the cutter being eccentric to that of the carrier, means for rotating the cutter and carrier, a pressure member non-rotatably mounted opposite the face of the carrier to engage the bodies of the blanks and hold them in place, a trimming cutter to engage the heads of the blanks as they are carried around by the carrier after being slotted by the slot-

ting cutter, means to rotate the blanks when in engagement with said trimming cutter, said rotating means and said trimming cutter both being carried by said pressure member, and spring means urging said pressure member toward the carrier.

5 8. A screw-slotting machine comprising a head, a ring-shaped carrier rotatably mounted in the head having means to receive the headed blanks and carry them in a circular path with their axes disposed substantially radially of the dial, a pressure pad supported by the head in opposed spaced relation to the carrier to engage the shanks of the blanks and hold them in said carrier, means mounting said pressure pad for movement toward and from the carrier, a member attached to said pressure pad for movement toward and from the carrier independently of said pressure pad, said member having means to engage the blanks and rotate them on their axes, and cutting means supported from the head on the side of the blanks opposite the carrier to trim the blanks while they are rotated by said member, and carried past said cutting means by the carrier.

10 9. A screw-slotting machine comprising a head, a ring-shaped carrier rotatably mounted in the head having means to receive the headed blanks and carry them in a circular path with their axes disposed substantially radially of the dial, a pressure pad supported by the head in opposed spaced relation to the carrier to engage the shanks of the blanks and hold them in said carrier, means mounting said pressure pad for movement toward and from the carrier, a member attached to said pressure pad for movement toward and from the carrier independently of said pressure pad, said member having means to engage the shanks of the blanks and rotate them on their axes, and cutting means to engage and trim the heads of the blanks while being rotated by said member, said cutting means being adjustably secured to said pressure pad.

15 10. A screw-slotting machine comprising a head, a ring-shaped carrier rotatably mounted in the head having means to receive the headed blanks and carry them in a circular path with their axes disposed substantially radially of the dial, a pressure pad supported by the head in opposed spaced relation to the carrier to engage the shanks of the blanks and hold them in said carrier, means mounting said pressure pad for movement toward and from the carrier, a member attached to said pressure pad for movement toward and from the carrier independently of said pressure pad, said member having means to engage the shanks of the blanks and rotate them on their axes, cutting means to engage and trim the heads of the blanks while being rotated by said member, said cutting means comprising a blade having a cutting edge on each end thereof, and said blade being securable in reversed positions on said pressure pad to direct either of said edges toward the work.

20 11. A screw-slotting machine having a stationary head, a ring-shaped carrier dial rotatably supported thereby for carrying the blanks in a circular path, and a rotating slotting cutter mounted eccentrically within said dial to engage and slot the screw blanks at one portion of their travel over said path, an arcuate member nonrotatably mounted on the head in opposed spaced relation to the dial to engage the bodies of the blanks and hold them in place in the dial, means on said member to effect rotation of the blanks in the dial at a following point in said path after they have been engaged by the slotting cutter, and nonrotatably mounted means to trim the burrs from the blanks as they are rotated in the dial and carried past said trimming means by rotation of the dial.

25 12. A screw-slotting machine as in claim 11 wherein said trimming means is mounted upon said arcuate member.

13. A screw-slotted machine as in claim 11 wherein said trimming means is mounted upon said arcuate member, and the latter is spring-urged toward the dial.
